UNITED STATES PATENT OFFICE

146,385

DESIGN FOR A RADIO RECEIVER CABINET

Lazarus C. Shapiro, New York, N. Y., and Floyd W. Flynn, Bellrose, N. Y., assignors to Premier Crystal Laboratories, Incorporated, New York, N. Y.

Application December 26, 1945, Serial No. 125,030

Term of patent 14 years

(Cl. D56—4)

To all whom it may concern:

Be it known that we, Lazarus C. Shapiro, a citizen of the United States, residing at New York, in the county of New York and State of New York, and Floyd W. Flynn, a citizen of the United States, residing at Bellrose, in the county of Queens and State of New York, have invented a new, original, and ornamental Design for a Radio Receiver Cabinet, of which the following is a specification, reference being had to the accompanying drawing, forming part thereof.

Figure 1 is a perspective view of a radio receiver cabinet, showing our new design.

Figure 2 is a transverse cross sectional view on

a reduced scale taken through the mid-portion of the radio receiver cabinet shown in Figure 1.

We claim:

The ornamental design for a radio receiver cabinet, as shown.

LAZARUS C. SHAPIRO.
FLOYD W. FLYNN.
